his Attorneys

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed November 1, 1922. Serial No. 598,325.

To all whom it may concern:

Be it known that I, CHARLES DAVID BONSALL, a citizen of the United States, and a resident of the city of Pittsburgh, county of Allegheny, and State of Pennsylvania, have invented a certain new and useful Improvement in Car Roofs, of which the following is a specification.

This invention relates to car roofs of the all-steel riveted-up type wherein self supporting roof sheets extend from side plate to side plate and are riveted thereto and to each other to form a rigid load sustaining structure.

One of the principal objects of the present invention is to increase the strength and rigidity of the roof by improving the sectional shape of the lapped portions of the sheets. Another object is to produce a durable and light weight roof of simple construction which can be easily assembled and cheaply manufactured. The invention consists principally in the improved seam construction hereinafter shown and described; and it also consists in the combinations and arrangements of parts hereinafter described and claimed.

In the accompanying drawing, which forms part of this specification and wherein like symbols refer to like parts wherever they occur.

Fig. 1 is a plan view of a portion of a car roof embodying my invention;

Fig. 2 is an enlarged transverse section through one-half of the car roof on the line 2-2 in Fig. 1.

Fig. 3 is a vertical cross section through one of the seams on the line 3-3 in Fig. 2;

Fig. 4 is a cross section through the eaves portion of the roof, the section being taken through one of the seams on the line 4-4 in Fig. 1; and

Fig. 5 is a cross section through the eaves portion of a seam on the line 5-5 in Fig. 4.

The present roof comprises transversely arranged load sustaining roof sheets 6, which extend from eaves to eaves of the car. The roof sheets are supported at their eaves ends on metal side plates 7 and are rigidly secured thereto by rivets 8; and the eaves ends of the roof sheets are provided with depending drip flanges 9 which overhang the outer edges of the side plates.

The roof sheets slope upwardly from the

eaves towards the ridge; and the side marginal portions of each roof sheet are pressed up in the form of stiffening ribs or seam flanges 10 and 11 of substantially inverted L-shape section; that is, each marginal portion has a substantially vertical web portion at the top of which is a laterally projecting flange portion; and the seam flange 10 of each sheet is provided at its outer margin with a shallow down-turned flange portion 10a.

The top flanges of the two inverted L-shaped side marginal seam flanges 10 and 11 of each sheet project laterally in the same direction; that is, the top flange of the seam flange 10 at one side of a sheet projects outwardly beyond the body portion thereof, and the top flange of the rib 11 at the opposite side of said sheet projects inwardly and overhangs the body portion thereof.

The roof sheets are assembled by placing the rib or seam flange 10 of one sheet over the rib or seam flange 11 of the next adjacent sheet with the web portions of the cooperating ribs or seam flanges in contact; and said lapped seam flanges are rigidly secured together by a row of rivets 12 that extend through the top flanges thereof. When thus assembled, the depending free marginal portion 10a of the upper seam flange 10 of each seam overhangs the free edge of the lower seam flange 11 of the seam and serves to waterproof the same. As shown in the drawing, the seam flanges 10 and 11 are of substantial uniform width and depth from ridge to points adjacent to the eaves where they are curved downwardly and merge into the plane of the body of the sheets at points where the ends of the sheets are turned down to form the drip flanges 9; but, if desired, said seam flanges may be of varying width and depth from ridge to eaves.

At the eaves, the laterally projecting top flange portion of the underlying seam flange of each seam is removed for a distance corresponding to the length of the downwardly curved eaves end portions thereof, thus leaving an up-standing flange at the eaves ends of said underlying seam flange whose upper edge is curved to correspond to the downwardly curved eaves end portions of the overlapping seam flange 10. The surplus of metal resulting from the down-turned eaves

end portions of the overlapping seam flange 10 is utilized to increase the depth of the depending free marginal portions 10^a thereof, whereby said seam flange 10 has eaves 5 end portions of inverted channel-shaped section; and at points adjacent to the eaves, where said marginal portion reaches the plane of the body of the sheets, it is turned outwardly to form lateral base flanges 10^b 10 which overlap the body portion of the adjacent sheet and are rigidly secured to the side plates by means of the rivets 8 that secure the eaves ends of the sheets thereto.

The seams or joints produced by the cooperating seam flanges or ribs 10 and 11 accomplish the various functions of carlines. The cross-sectional shape of the seams at the ridge serves to increase the load carrying capacity of the roof, and the cross-sectional shape of the seams at the eaves serves to take care of the stresses that tend to rack and twist the car body and distort it endwise. This increased strength in the seam enables a roof to be produced that will be 25 stiffer and stronger than previous roofs of the same weight of metal.

Running boards 13 are arranged lengthwise of the roof at the ridge, and are bolted or otherwise rigidly secured to the lateral flanges of running board saddles 14. The running board saddles rest on and are rigidly secured to the tops of the seam by means of the rivets 12 that secure the lapped seam flanges together.

35 The top of the downwardly curved inverted channel-shaped eaves end portion of each seam flange 10 is provided with an opening 15. These openings permit the escape of water or cinders that may accumulate in the 40 inverted channel-shaped eaves ends of the seams.

The invention is not restricted to the precise form and arrangements shown in the accompanying drawing.

45 What I claim is:

1. A car roof comprising a plurality of rigid load-sustaining roof sheets extending from eaves to eaves and having their adjacent side marginal portions formed into upstanding seam flanges, each of said seam flanges comprising a substantially vertical web portion at the top of which is a laterally projecting flat flange portion, the seam flanges of adjacent sheets being disposed 50 web to web with their laterally projecting flat flange portions lapped and rigidly secured together to form waterproofing seams that constitute stiffening members for the car, the overlapping flat flange portion of 55 one seam flange of a seam being turned down over the free edge of the underlying portion of the other seam flange of said seam, the downturned portion of the overlapping seam flange of each sheet being of 60 increased depth adjacent to the eaves where 65

it is turned outwardly in the plane of the body of the next adjacent sheet and rigidly secured thereto.

2. A car roof comprising a plurality of roof sheets extending from eaves to eaves 70 and having their adjacent side marginal portions formed into upstanding seam flanges whose eaves end portions are curved downwardly and merge into the sheets at the eaves ends thereof, each of said seam flanges comprising a substantially vertical web portion having at the top thereof a laterally projecting flange portion, the seam flanges of adjacent sheets being disposed 75 web to web with their lateral flange portions lapped and rigidly secured together, the overlapping lateral flange portion of a seam being provided adjacent to the downwardly curved eaves end portions thereof with an opening and the underlying lateral 80 flange of said seam terminating short of said opening to permit the escape of cinders and water therethrough.

3. A single-course car roof comprising a plurality of self-sustaining roof sheets extending from eaves to eaves and having their adjacent side marginal portions formed into upstanding seam flanges whose eaves end portions are curved downwardly and merge into the sheets at the eaves ends thereof, each of said seam flanges comprising a substantially vertical web portion having at the top thereof a laterally projecting flange portion, the seam flanges of adjacent sheets being disposed 90 web to web with their lateral flange portions lapped and rigidly secured together, the overlapping lateral flange portion of a seam being turned down over the free edge of the underlying lateral flange thereof, the said down-turned portion being turned outwardly adjacent to the downwardly curved eaves ends of said seam and riveted to the underlying body portion 95 of the sheet adjacent thereto.

4. A car roof sheet having its side marginal portions formed into hollow ribs having downwardly curved eaves end portions, a portion of the top of each of said ribs being removed adjacent to its downwardly curved eaves end portions to form openings therein.

5. A car roof sheet having its side marginal portions formed into upstanding seam flanges whose eaves end portions are curved downwardly and project on the plane of the body of the sheet adjacent to the eaves ends thereof, each of said seam flanges comprising a substantially vertical web portion having a lateral top flange, the lateral top flange of one seam flange extending 110 outwardly beyond the body of the sheet and the lateral top flange of the other seam flange extending inwardly and overhanging the body portion of said sheet, the lateral top flange of one seam flange being provided 115 120 125 130

along its free marginal edge with a depending flange whose depth is increased adjacent to the eaves where it terminates in the form of a lateral base flange, the lateral top flange of said last mentioned seam flange having an opening therein adjacent to its downwardly curved eaves end portions, and the other seam flange having a portion of its lateral top flange removed adjacent to its 10 downwardly curved eaves end portions.

6. A car roof comprising a plurality of roof sheets whose side marginal portions are connected by seams of substantially L-shaped section at the ridge and of substantially channel-shaped section adjacent to the eaves.

7. A car roof comprising a plurality of

roof sheets whose side marginal portions are positively connected by rigid upstanding seams of substantially inverted L- 20 shaped section at the ridge and of substantially inverted channel-shaped section at the eaves.

8. A single-course car roof comprising a plurality of self-sustaining roof sheets whose 25 side marginal portions are positively connected by rigid seams that function as car-lines, said seams being of substantially L-shaped section at the ridge and of substantially channel-shaped section adjacent to 30 the eaves.

Signed at New Kensington, Pennsylvania,
this 26th day of October, 1922.

CHARLES DAVID BONSALL.
